UNITED STATES PATENT OFFICE.

CHARLES A. PERSONS, OF WORCESTER, MASSACHUSETTS.

SPRING-SADDLE.

1,186,603.

Specification of Letters Patent. Patented June 13, 1916.

Application filed December 8, 1914. Serial No. 876,044.

To all whom it may concern:

Be it known that I, CHARLES A. PERSONS, a citizen of the United States, residing at Worcester, in the county of Worcester, State 5 of Massachusetts, have invented a certain new and useful Improvement in Spring-Saddles, of which the following is a specification, reference being had therein to the accompanying drawings.

10 This invention relates to seats or saddles but more particularly to such as are adapted for use on velocipedes, bicycles, motorcycles and the like and has for its object to provide a structure which is more simple and efficient 15 in operation than any device of a similar nature heretofore known.

It has heretofore been common practice 20 to make a form of cantle supporting spring in which the compression and extension springs forming the same are placed substantially end to end so that they had the appearance of being all in one part, and the compression spring was quite generally made in a conical form for neatness in appearance 25 and freedom of action, though this was not essential. The extension spring was generally suspended from the supporting frame or truss by its upper extremity in the manner common to compound spring supports and 30 the lower extremity of the compression spring was secured to the same bolt as the upper extremity of the corresponding extension spring by an eyelet looping such bolt. Within these two springs and substantially 35 coaxial therewith passes a depending rod having its upper extremity secured to the under side of the seat and its lower extremity connected to the corresponding lower extremity of the extension spring.

40 The upper extremity of the compression spring coats with a shoulder on such rod so that a depression of the rod due to a shock compresses the compression spring and extends the extension spring simultaneously.

45 This spring is so constructed that no adjustment is possible by the rider.

In order to provide a spring support of the type described, but which is capable of easy adjustment to suit the different riders, 50 a form of spring support and means for attaching the same to the seat supporting

frame or truss has been devised in which the spring action may be readily adjusted at any time.

Referring to the drawings:—Figure 1 is a 55 rear elevation of a saddle complete in which one of the cantle supports is in section and the other is shown in full, as will be fully described hereinafter. Fig. 2, central vertical section of a modified form of the invention, as will be fully described hereinafter. 60

In the drawings the embodiment shown in Fig. 1 comprises a seat 10 mounted on a supporting frame here composed of trusses 12 and 13, respectively composed of the upper 65 wires 14 and 15 and the lower wires 16 and 17. As these two trusses or frames are substantially the same except that their parts are reversed and as the particular type forms no part of the present invention, no detailed description of the same will be given here as their construction is well known in the art and any form of truss or frame may be substituted for the one shown in the drawing. 75

Through eyelets formed in the rear extremities of the trusses 12 and 13 pass bolts 18 and 19 which are provided at their outer extremities with clamping heads 20 and 21 respectively adapted to grip two adjacent 80 coils of the compression springs 22 and 23 respectively in the manner shown in Fig. 1.

In the embodiment shown in Fig. 1 the compression springs 22 and 23 and their respective extension springs 24 and 25 are 85 formed integral by merely varying the winding in the two portions of the spring. As the springs on each side of the cantle are the same, only that composed of the compressible portion 22 and the extensible portion 24 will be described as such description will apply equally to the spring composed of the compressible portion 23 and the extensible portion 25. 90

For brevity of description the compound 95 spring composed of the portions 22 and 24 will be hereinafter referred to as the spring 26. The lower extremity 27 of this spring 26 is here formed into an eyelet and clamped to the lower extremity of the depending rod 100 28 in the manner common to compound spring supports, and the upper extremity of

the compression portion 22 coacts with a shoulder 29 here formed on the rod 28 which extends upwardly within the coils of the spring 26 preferably substantially coaxial therewith.

In the embodiment of the invention shown in Fig. 1 of the drawings, the two lowest coils of the compression portion 22 of the spring 26 have been engaged by the clamping head 20 of the bolt 18, but this may be readily adjusted by loosening the binding nut 30 on such bolt and turning the spring within the head until the head grips the next two coils above those shown engaged, or, in fact any two adjacent coils that may be desired, and thus the number of coils acting as a compression spring will be varied, for all those below the bolt 18, which fastens the spring to truss, will act as extension spring coils, even though they have been wound in the manner usual for a compression spring. To move the binding post or bolt 18 upwardly relative to the spring tends to stiffen the compression element and correspondingly render more yielding the extension element. By so adjusting the relative resistance of the compression and extension element, the rider can secure the spring action which produces the greatest comfort for his particular weight, aside from many other advantages which will be readily evident to one skilled in the art.

In the embodiment shown in Fig. 2, the extensible and compressible elements 31 and 32 respectively of the cantle supporting springs are separate springs instead of being formed integral in the manner previously described for the embodiment of Fig. 1 and the extensible element has its upper extremity formed into an eyelet 33 which fits about the bolt 34, corresponding to the bolt 18 in the previous embodiment, and is provided with a clamping head 35. This bolt 34 engages the rear extremity of the truss in the same manner as was described in connection with Fig. 1 and this head 35 engages the two next adjacent coils of the compressible spring 32. The compressible spring is preferably of different coil diameter than that of the extensible spring so that they may telescope. In the particular embodiment shown in Fig. 2, the compressible element is of smaller diameter than the extensible element so that when the clamping post or bolt 34 is moved upwardly to engage the second and third or third and fourth instead of the first and second coils as shown in the drawings, the lower extremity of the compressible element will rest within and be enveloped by the upper coils of the extensible element. Thus the same adjustability is obtained as with the embodiment shown in Fig. 1 of the drawing.

The applicant is aware that numerous changes in the arrangement and construction of parts may readily be made by any one skilled in the art without departing from the scope of his invention and he does not care to be limited to the particular embodiments herein shown and described.

What I claim as my invention and desire to secure by Letters Patent is:—

1. In a device of the class described, a frame, a seat, and means for resiliently supporting said seat, comprising coil compression springs interposed between said seat and said frame, and means for engaging the coils of each of said compression springs on one side thereof to secure the same to said frame.

2. In a device of the class described, a frame, a seat, and means for resiliently supporting said seat comprising a pair of coil compression springs interposed between said seat and said frame and means for selectively securing at the same time more than one coil of each of said compression springs to said frame to provide a support of variable rigidity.

3. In a device of the class described, a frame, a seat, and resilient supporting means for said seat, each comprising a coil spring, and means for selectively engaging more than one coil of said spring on one side thereof and intermediate its ends to bind the same to said frame.

4. In a device of the class described, a frame, a seat, and resilient supporting means for said seat comprising coil compression springs interposed between said seat and said frame, and means coacting with the frame for securing each of said springs to said frame comprising a bolt provided with a binding head adapted to engage more than one coil of the spring.

5. In a device of the class described, a frame, a seat, and resilient supporting means for said seat comprising a compression spring, an extension spring integral therewith and forming an extension thereof, and means for engaging the coils of one of said springs to secure the combined spring to said frame.

6. In a device of the class described, a frame, a seat, and a resilient support for said seat comprising an extensible element and a compressible element formed of a single piece of wire, and means for engaging said compressible element at any point in its length to secure such elements to said frame.

7. In a device of the class described, a frame, a seat, and supporting means for said seat comprising an extensible spring suspended by substantially its upper extremity from said frame, a rod depending from said seat and having substantially its

lower extremity secured to the corresponding lower extremity of said extensible spring and a compressible spring having its upper extremity coacting with said seat, and means 5 for attaching said compressible spring at substantially any point in its length to said frame.

In testimony whereof I affix my signature in the presence of two witnesses.

CHARLES A. PERSONS.
